UNITED STATES PATENT OFFICE.

OTTO LAUENSTEIN, OF WERNIGERODE, HARZ, GERMANY.

WRAPPING DEVICE FOR IRREGULARLY-SHAPED DELICATE OBJECTS.

Application filed August 25, 1925, Serial No. 52,411, and in Germany August 29, 1924.

This invention has reference to means for the wrapping up of material with a flexible wrapper, die, envelope or the like, and it refers in particular to means of the kind referred to adapted for the covering of sensitive, or soft and irregularly shaped material, such as different kinds of candies, sweets, fudge, so-called "pralines," and equivalent articles, and it is intended to generally improve devices of the kind referred to, to facilitate and accelerate the wrapping process, and to insure the turning out of a high-grade product of neat appearance. In accordance with this invention the article to be wrapped is treated with a yieldable die or wrapping means, comprising in the preferred embodiment of the invention rollers or the like which are provided with a soft or yieldable coating, such as for instance, a coating of bristles, soft felt, sponge rubber, a plurality of soft yieldable rubber fingers or the like. These rollers are preferably rotated in a direction opposite to the feeding or propelling of the articles to be wrapped. In further pursuance of this invention these rollers or the like may be spring journaled, so as to prevent the injuring of articles of particularly irregular shape. In one of the most preferred constructions of this invention two pairs of rollers with intersecting axes in two different planes are employed. The longitudinal section of the rollers may adapt itself as much as possible to the cross sectional shape of the articles to be wrapped up. Particularly in the case of pairs of rollers disposed in different planes such rollers may be adjustable, so as to adapt them to different sizes of articles and to admit of a change of distance of the axes of the rollers from each other.

The invention will be more fully described with reference to the accompanying drawing which show several embodiments thereof, without, however, limiting the invention thereto.

In the drawings:—Figure 1 is a vertical cross section through a device according to this invention on the line I—I of Figure 2. Figure 2 is a front view of the device. Figure 3 is a plan view of this form of construction of the device; the upper portion

of the device which is intended to complete the wrapping operation and which is constructed in the usual manner has been omitted for the sake of simplicity and of clearness of illustration. Figure 4 illustrates in a somewhat diagrammatic manner a front view of a modification. Figure 5 is a plan view thereof, and Figure 6 shows one of the rollers employed in connection with this embodiment on an enlarged scale.

In connection with the modification according to Figures 4 and 5 different forms of construction of rollers are shown with one and the same device, merely by way of simplifying the illustration, but it is obvious that as a rule only one kind of rollers will generally be employed with the device, but without restricting the invention to any particular embodiment or combination of embodiments. In the form of construction according to Figures 1 to 3 two pairs of rollers 1 and 2 are mounted respectively on shafts 5 and 12 and below each other and in such a manner that the directions of the shafts 5 and 12 will intersect. Said shafts 5 and 12 are mounted in rockable arms 8 and 9. The arms 8 carrying the upper rollers 1 are rockably mounted on the studs or bolts 3, and the arms 9 carrying the lower rollers 2 are rockably secured on the studs or bolts 4. The arms 8 and 9 are adjustable relatively to each other and are acted upon by springs 10 adapted to force the rollers in the inoperative position against the adjustable stops 11. Upon adjustment of the said stops 11 and owing to the rockable mounting of the arms 8 and 9 and the tension of the springs 10 thereon the said arms may be moved toward or away from each other, as apparent. The driving of the rollers is effected by pairs of gear wheels 7, 7^a, and the gear wheels 7 are rigidly connected to the shafts 5 and 12 respectively of the rollers. The gear wheels 7^a, however, are rotatably mounted upon the rocking shafts 3 and 4 respectively of the levers 8 and 9, and are operated by sprocket wheels 13.

The rollers 1 and 2, as above mentioned, are provided with a soft coating, thus for instance, with sponge rubber, bristles or the like. The direction of movement of the roll-

ers is indicated by the arrows A in Figure 1. The mode of operation of the device is substantially as follows:—The article 15, a piece of candy or the like, is mounted in the well known manner upon the stem 14. Between the guide plates 16 the wrapper 17, consisting for instance of tin foil, is introduced which is cut to the desired lengths by any suitable cutting device. The stem 14 which is upwardly projected by the driving means forces the article 15 through the recesses 18 of the guide plates 16, and in this movement the tin foil is carried along and is gently placed around the article. The stem then pushes the article first through the lower pair of rollers, and then through the upper pair of rollers, and the soft coating of the rotating rollers during this movement gently and snugly forces the wrapper in contact with the article. Above the pair of rollers 1 a receiver of well known construction is arranged which is adapted to fold down the marginal parts of the wrapper which project from the main surface of the article. The rotation of the wrapping rollers or dies produces a particularly close and snug contact and high gloss of the wrapping sheet.

In the modified form of construction according to Figures 4 to 6 the rollers possess a longitudinal sectional shape particularly adapted to correspond to the cross sectional shape of the object to be wrapped. In this modification the coating of the rollers may be less resilient. In order to facilitate the manufacture of these rollers, they may be composed of a plurality of discs 20 secured upon the hub portions 21, as appears from the representation at 19 and 22. These individual parts may be formed of soft rubber or of any other yielding material. In this modified construction there may likewise be provided a yielding manner of journaling the shafts of the rollers combined with the yielding or resilient construction of the rollers themselves.

The invention has been shown and described in its broad principal aspects only, and it should be understood that it is not limited to the particular embodiments shown by way of exemplification only, but it is susceptible of other modifications and changes, as will suggest themselves to the expert, except as defined in the claims hereunto appended.

I claim:—

1. In a wrapping device for irregularly shaped delicate objects, means for placing a wrapper on said objects, and smoothing means mounted to move in a direction towards the margin of the wrapper while on the object and adapted to gently press the wrapper in contact with the object.

2. In a wrapping device in combination, means for placing a flexible wrapper upon

an object, smoothing means adapted to assume substantially the outer shape of said object and in moving contact with said wrapper in a direction towards the marginal edge of the wrapper for partly forcing and smoothing the wrapper in contact with the object.

3. In a wrapping device in combination, movable guiding means for the object to be wrapped, means for placing a flexible wrapper on the object, while on the guiding means pairs of rockably mounted rollers movable in opposition to said guiding means and said object and on opposite sides thereof, and adapted to gently force the wrapper in close and snug contact therewith.

4. In a wrapping device in combination, axially movable guiding means for the object to be wrapped, means for placing a flexible wrapper upon the object, while on the guiding means, superimposed and axially intersecting pairs of rockably and yieldably mounted rollers movable in opposition to said guiding means and said object and on opposite sides thereof, and adapted to gently force the wrapper in close and snug contact therewith.

5. In a wrapping device in combination, movable guiding means for the object to be wrapped, means for placing a flexible wrapper on the object, while on the guiding means, pairs of rockably and yieldably mounted rollers rotating in opposition to the guiding means and having a coating of bristles thereon adapted to gently force and smooth the wrapper into close contact with the object.

6. In a wrapping device in combination, axially movable guiding means for the object to be wrapped, means to place a flexible wrapper on said object, while on the guiding means, pairs of rockably mounted spring actuated rollers movable in opposition to said guiding means and said object and in opposition thereof, and adapted to gently force the wrapper into engagement with the object.

7. In a wrapping device in combination, axially movable guiding means for the object, means to place a flexible wrapper on said object while on the guiding means, pairs of rockably mounted rollers movable in opposition to said guiding means and said object and having a coating of bristles thereon adapted to become snugly engaged with the wrapper on the object.

8. In a wrapping device for irregularly shaped objects, axially movable supporting means for the objects, laterally yielding rollers on both sides of the supporting means, means to adjust the distance of the rollers from each other and the supporting means, and means to place a flexible wrapper on the object, while on the supporting means.

9. In a wrapping device for irregularly

shaped objects and the like an apertured guide for the wrapper, supporting means adapted for the mounting of the object to be wrapped and axially movable through said apertured guide, and adapted to cause the seating of the wrapper on the object, yieldingly disposed, adjustably spaced pairs of smoothening rollers engageable on both sides of the axially movable supporting means, and driving means for said rollers. **10**
In testimony whereof, I affix my signature.

OTTO LAUENSTEIN.
